(57) **CLAIM**

The ornamental design for a nasal cannula assembly, as
shown and described.

DESCRIPTION

FIG. 1 is a top, front and right side perspective view of a
nasal cannula assembly embodying our new design.

FIG. 2 is a top, rear and right side perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

The broken lines in the drawings depict portions of the nasal
cannula assembly that form no part of the claimed design.
